United States Patent Office

Des. 189,796
Patented Feb. 21, 1961

189,796

AWL

Jerome L. Murray, New York, and Donald P. Pollard,
Bayside, N.Y., assignors to William Thomas & Sons,
Inc., Ridgefield, N.J., a corporation of New York

Filed May 13, 1960, Ser. No. 60,560

Term of patent 14 years

(Cl. D54—13)

Fig. 1 is a front elevational view of an awl embodying our new design, the rear view being substantially the same; and

Fig. 2 is a top plan view thereof.

The portions stippled in the drawing contrast in color with the unstippled portions.

We claim:
The ornamental design for an awl, substantially as shown and described.
